DESIGN FOR A COMBINED TUMBLER AND TOOTHBRUSH HOLDER

Chester D. Klauber, New York, N. Y., assignor to The Fairfacts Company, Inc., New York, N. Y., a corporation of New York

Application March 2, 1945, Serial No. 118,232

Term of patent 7 years

(Cl. D4—3)

To all whom it may concern:

Be it known that I, Chester D. Klauber, a citizen of the United States, residing in New York, in the county and State of New York, have invented a new, original, and ornamental Design for a Combined Tumbler and Toothbrush Holder, of which the following is a specification, reference being had to the accompanying drawing forming part thereof, in which

Figures 2 and 3 are, respectively, front and side elevations of the same; and

I claim:

The ornamental design for a combined tumbler and toothbrush holder, substantially as shown.

CHESTER D. KLAUBER.
